UNITED STATES PATENT OFFICE.

CORNELIUS TIERS, OF MADISON, NEW JERSEY, AND JOHN H. PENDLETON,
OF BROOKLYN, NEW YORK.

RAILWAY.

SPECIFICATION forming part of Letters Patent No. 311,045, dated January 20, 1885.

Application filed April 19, 1884. (No model.)

To all whom it may concern:

Be it known that we, CORNELIUS TIERS, of Madison, in the State of New Jersey, and JOHN H. PENDLETON, of Brooklyn, E. D., in 5 the State of New York, have invented an Improvement in Railways, of which the following is a specification.

Elevated railways have heretofore been constructed over streets and avenues in cities, 10 and the same streets have been used for surface railways in which the cars are drawn by horses.

The object of our present invention is to avail of the elevated railways for supporting 15 a traveling wire rope for drawing the cars of the surface railway, thereby dispensing with the use of horses, and causing the surface road to be transferred into a cable road, the cable being elevated and supported beneath 20 the elevated-railway structure.

In carrying out this invention we suspend 25 beneath the elevated railway a track upon hangers, which track carries a traveling carriage and device for clamping the cable, and the cable runs over rollers in stationary bearings upon the hangers. From the traveling carriage there is a connection to the railway-car to draw the same along upon the surface-railway.

30 In the drawings, Figure 1 is a cross-section of the elevated railway and of the track below the same. Fig. 2 is a longitudinal section, showing in elevation the girder, track, and the carriage that is used for drawing the 35 cars on the surface road; and Fig. 3 is a sectional elevation, showing the hangers, cross-bar, track, sheaves, and cables.

The elevated railway is composed of the 40 columns or supports A A, the cross-girders B, and longitudinal girders C C, in any of the known forms.

Our invention relates to the combination, 45 with the elevated-railway structure, forming a support, of sheaves or wheels D, suspended below the elevated structure by suitable brackets or hangers, so that the endless traction-cable or wire rope F may travel in the air above the street-cars G, which are to be drawn along on the tracks H at the surface

of the roadway by any suitable connection 50 between such cable F and car G. This cable is to be endless and moved by stationary engines, as usual.

In carrying out our said invention, it is necessary to provide a track, K, running 55 longitudinally and parallel with the cable, such track K being suspended by the hangers below the elevated railway, and upon this track K there is a traveling carriage, M, with grooved rollers both above and below 60 the rail, so that said carriage is free to roll along upon the track, but cannot become disconnected, and this carriage is connected to the car upon the surface railway by a traction-rope or any suitable appliance, and upon 65 the carriage M there is a clamping device or grip, by means of which the carriage is connected with and moved by the cable, or by which the hold upon the cable is relieved, so that the car may be stopped by the brakes, 70 as usual. The hangers are shown as made of the vertical portions E E and transverse horizontal bar E', to the ends of which the rails are fastened.

Grips of various kinds have before been 75 used upon cable roads. Our invention does not relate to any particular grip or clamp, and we remark that a grip may be used on our cable road similar to that heretofore employed in other cable roads, except that the 80 device for actuating the grip extends downwardly to the car below, instead of upwardly to the car above, as heretofore usual.

The details of construction of the respective parts are not our invention and are not herein 85 further described, the same being the invention of John H. Pendleton, and form the subject of a separate application, No. 128,476, April 19, 1884, by him for a patent. Hence the features of invention not herein claimed 90 by us are expressly reserved to be claimed by the said Pendleton.

We claim as our invention—

The combination, with the elevated structure composed of columns and cross and longitudinal girders, of hangers below such girders, sheaves or grooved wheels supported by such hangers, an endless cable upon such

wheels and actuated by competent power, a track suspended or supported by hangers below the elevated structure, a carriage upon such track, a connection from the same to a 5 car upon a surface railway, and a clamp or grip to connect the carriage with the cable, so as to be moved thereby, substantially as set forth:

Signed by us this 12th day of April, A. D. 1884.

CORNELIUS TIERS.
J. H. PENDLETON.
